UNITED STATES PATENT OFFICE.

ESOM O. LEACH, OF FAIRMOUNT, INDIANA.

MOLD-SANDING MACHINE.

SPECIFICATION forming part of Letters Patent No. 533,541, dated February 5, 1895.

Application filed April 9, 1894. Serial No. 506,868. (No model.)

To all whom it may concern:

Be it known that I, ESOM O. LEACH, a citizen of the United States of America, residing at Fairmount, in the county of Grant and 5 State of Indiana, have invented certain new and useful Improvements in Mold-Sanding Machines, of which the following is a specification, reference being had therein to the accompanying drawings.

10 This invention relates to mold sanding machines to be used in connection with steam power brick making machines.

The object of the invention is to dispense with the help usually required for sanding 15 the molds, increase the output of a machine of given capacity, preventing the waste and the scattering of the sand and obtain an even and uniform sanding of the molds.

The improvement consists of the organized 20 machine and the novel construction and combination of the parts which will hereinafter be more fully described and claimed.

In the accompanying drawings,--Figure 1 is a side elevation of a machine embodying 25 the invention, showing the operation of the same, a mold about to be dropped into the sand box, one in position to be removed and others sanding. Fig. 2 is a top plan view of the machine. Fig. 3 is a detail view of the 30 adjustable bearings and the means for moving the same to throw the machine in and out of gear.

Similar letters refer to corresponding parts in the several views.

35 The sand box is composed of two ends or heads A, preferably of cast iron, and a semi-circular casting B, of sheet metal, steel being preferred. The edges of the casing are let into grooves provided in the heads and the 40 latter are secured in place in any desired manner preferably by the rods C, which pass through apertured ears a, on the heads.

A shaft D, journaled in the heads A, is provided at one end with a gear wheel d, 45 meshing with a pinion f, on a short shaft F. Upon this shaft D, is mounted the mold carrier consisting of heads G, and sand lifting plates H. The heads G, are open spiders, the spokes radiating from tubes keyed to the 50 said shaft D. The perimeter of the heads has a corresponding series of straight faces i, j, k. The faces k, extend approximately

radially and the faces j, at right angles to the faces k. The faces i, incline from the faces k, and form seats for the plates H, 55 which are secured thereto. The contiguous faces j, and k, form seats for the molds, one closed side of the mold resting on the face k, and the open side on the edges j. The forward or advancing edges h, of the plates H, 60 project beyond the faces k, to approach close to the bottom portion of the casing B, to scrape up the smallest amount or quantity of sand in the box. The plates may be imperforate or have openings as required. 65

A bracket K, is attached to the head of the box and forms a support for a movable bearing box k', in which is journaled the shaft F. Parallel slots are provided in the brackets to receive bolts n, by means of which the said bearing box is held on the brackets. A stub-shaft O, journaled in the bearing box k, and adapted to be turned by a suitable handle o, has an eccentric portion p, which works in a transverse slot P, in the bracket K. On 75 turning the stub-shaft the bearing box will be moved to bring the pinion f, in or out of gear with the gear wheel d, as required. The band wheel Q, is keyed on the shaft F. The gearing is such that when the machine is run 80 at the required speed a mold will be sanded and brought into position for removal at each operation of the plunger of the brick making machine. In the machine shown four sets of edges i, j, k, are represented. It will be understood that this number may be varied to 85 suit the capacity of the machine.

When in operation the mold carrier is rotated in the direction of the arrow shown in Fig. 1, the molds being placed in the sand 90 box at S, and removed therefrom at T. The box is filled with sand to the depth of five or six inches. The faces k, engage with a closed side of the mold and carries the latter around to the position T where it is supported by the 95 face j. The plates H, scoop up the sand and throw it into the mold immediately in the rear and following said plate.

I claim—

1. In a mold sanding machine, a rotary 100 mold carrier having heads disposed about their peripheries in co-incident relation a series of faces, some of which extend approximately radially from the carrier, others at

right angles to the radial faces, and others inclining from the said right angularly disposed faces and located between them and the said lateral faces, and sand lifting plates secured 5 to the inclined faces, substantially as described.

2. In a mold sanding machine, a rotary mold carrier comprising heads mounted upon a shaft and located a distance apart, and having formed in their edges a series of faces, some on radial lines, others at right angles to the radial faces, and some inclining from the relatively disposed faces and located between them and the radial faces, and sand lifting plates extending across the space between the heads and fixedly secured to the inclined faces and having their advancing edges projecting beyond the radial faces, substantially as described.

3. The herein specified sand molding machine, composed of a semi-circular casing, ends having grooves on their inner faces to

receive the edges of the said casing, rods exterior to the casing and passing through apertured ends provided on the said ends to secure the latter and the casing together, a shaft journaled in the ends, actuating mechanisms for the shaft secured to one of the ends and adapted to be thrown in and out of gear with the said shaft, open spiders secured 30 to the shaft, one near each end, and having radial faces, seats at right angles to the said faces, and inclined edges between the seats and the said faces, and sand lifting plates secured upon the inclined edges and extending across 35 the space between the spiders, and having their advancing edges projecting beyond the radial faces, substantially as described.

In testimony whereof I affix my signature in presence of two witnesses.

ESOM O. LEACH.
